UNITED STATES PATENT OFFICE.

JOHN LOLO LEE, OF SHERRILL, NEW YORK, ASSIGNOR TO ONEIDA COMMUNITY LIMITED, OF ONEIDA, NEW YORK, A CORPORATION OF NEW YORK.

DISPLAY CHEST FOR SILVERWARE, ETC.

Application filed July 3, 1922. Serial No. 572,390.

To all whom it may concern:

Be it known that I, JOHN LOLO LEE, a citizen of the United States, resident of Sherrill, county of Oneida, State of New York, have 5 made a certain new and useful Invention Relating to Display Chests for Silverware, Etc., of which the following is a specification, taken in connection with the accompanying drawing, which forms part of the 10 same.

This invention relates especially to display chests or cabinets for silverware or other generally similar articles in which the chest may be formed with one or more laterally swinging wing sections, each of 15 which comprises one or more wing shelves to accommodate articles so that these wing sections can be swung outward to expose still other articles in the lower part of the chest 20 which may advantageously be arranged in a slideable or removable drawer or tray in the chest in which sets of articles may be arranged, similar articles being superimposed, if desired, in the same supporting slot in the 25 tray. These slots may be formed in any suitable spacing blocks and are preferably lined with velvet or other fabric while vertically adjustable gripping supporting blocks having similar facing fabrics, if 30 desired, may be forced into these supporting slots so as to be in the proper vertical position to accommodate the number of articles in this particular set of spoons, forks or the like. The chest cover may also be 35 provided with apertured supports for articles such as knives which may be arranged to appear in attractive spaced position when the cover is opened up.

In the accompanying drawing showing in 40 a somewhat diagrammatic manner various illustrative embodiments of this invention

Fig. 1 is a perspective view of an illustrative display chest.

Fig. 2 is a partial vertical section thereof.

Fig. 3 is a horizontal sectional view showing the bottoms of the wing shelves.

Fig. 4 is an enlarged detail view showing the shelf retainer construction.

Fig. 5 is an enlarged sectional view of the 50 spacing blocks.

Fig. 6 is a perspective view of the supporting block therefor, and

Fig. 7 is a perspective view showing another illustrative form of chest.

The silverware cabinet or display chest 55 may be of any suitable construction and may be formed of heavy durable wood such as mahogany, walnut, etc., the chest bottom 44 being preferably permanently joined or framed to the lower side sections 4 and the 60 back and also the adjacent back extensions 2 if desired. The framed chest cover 1 may be hinged to this back and back extensions by any suitable cover hinges such as 3 and any desired hinge arrangement may be employed to connect the laterally swinging wing sections to this chest on one or both sides of the same.

These wing sections may, as indicated in Fig. 1, each comprise an upper side section 65 to which the one or more wing shelves 12 are rigidly connected and which is preferably disengageably hinged to the chest by the hinge 9 which may have the removable pin 8 which on its withdrawal allows the 70 corresponding wing section to be removed for cleaning etc. In this Fig. 1 construction the wing section comprises a supporting front section 7 rigidly framed to the upper side section 6 and to the wing shelf 12 and 75 this front section, when swung around into closed position constitutes a front of the chest as seen at the right of Fig. 1. This front section can thus rest on the support on which the chest bottom rests and reliably 80 support the wing section in any position in which it may be swung out so that excessive strain on the hinges etc. is thus prevented. In this connection it is usually desirable to have cushioning fabric such as felt, etc. 85 glued to the bottom of this supporting front section 7 as at 22' and a similar felt or other cushioning fabric 22 may be glued or secured to the bottom 44 of the chest. To further guide the wing section in its swinging 90 movements it is desirable to have a suitable retainer device arranged between the wing shelf and the chest so as to guide the shelf in its swinging movement and prevent its being unduly raised and for this purpose a circular retainer groove such as 15 may be formed in the lower face of the wing shelf 12 as shown in Fig. 4 and a retainer plate 16 of fiber board or other strong material may be

2

screwed or nailed to the shelf to project part way over this retainer groove so as to form a dovetailed groove or retainer recess in which the retainer hook or member 17 on the lower side section 4 engages throughout the swinging movements of the wing shelf. This construction is also illustrated in Fig. 3 where the lower surfaces of these wing shelves are shown in this bottom view. Aligning members are desirable on these wing sections and chest body so as to definitely hold them in closed position and for this purpose aligning slots such as 10 may be formed in each of the wing sections adjacent the free end of the supporting front section so that when the wing section is swung into closed position this slot comes into engagement with an aligning pin or member 11 projecting from the chest bottom 44 so as to vertically align these two parts and strengthen the chest considerably, especially when it is locked by any suitable locking devices, 19, 20. The wing shelf 12 may be formed with a velvet or other suitable lining and with raised supporting members 13 so as to accommodate the silverware articles 14 which when the wing section is swung into closed position are arranged in the desired relation to the other articles in the chest and the rear portion of the chest may be formed with a rear shelf 26 on about the same level as these wing shelves and may be provided with similar supporting members 27 to accommodate still other articles if desired.

The lower part of the chest may be provided with one or more spacing blocks such as 21 to accommodate sets of different articles such as spoons or forks of different sizes or styles, the different forks of a single set being, if desired, superimposed upon one another in one or more of the supporting slots 22 formed in the spacing blocks which may advantageously be arranged in a removable tray or drawer 5. As shown in Fig. 5, these supporting slots 22 are preferably formed with velvet or other fabric lining 23 of the same style and color as the facing on the top of the block. If desired also vertically adjustable gripping supporting blocks may be arranged in these slots and may be formed with a wooden body 24 and a velvet or other fabric facing 25 so that when the blocks are forced into the slots they tightly engage the same and these two layers of fabric are forced together so as to more or less grippingly engage or interlock their fibers and tightly hold the supporting block in any adjusted position, it being of course understood that the thickness of these fabric layers is considerably exaggerated in Fig. 5 for the sake of clearness. In this way the supporting block may be arranged adjacent the top of the slot when only a few articles are to be inserted as shown at the right of Fig. 5 and when,

for instance, further articles of this same set or style are purchased, the supporting block may be pushed further down in its slot as shown at the left of Fig. 5 so as to accommodate the additional articles and still leave the upper articles nearly or substantially flush with the top of the spacing block 21 when the articles are all in the slot. This gives the chest a desirable expanding capacity so that in this bottom section or removable tray 5 fifty or one hundred additional articles may be accommodated under some conditions.

If desired, the chest cover may be formed with one or more cover supports 40, 43 in which supporting apertures 42 may be formed for still other articles such as the knives 14 so that when the chest cover is opened up these knives are seen in spaced relation to each other and are also readily accessible for removal. The wing sections when swung out expose to view the articles in the chest bottom or removable tray below so that by simply swinging outward both of these wing sections all of the articles in the entire chest are exposed to view and can be readily removed if desired.

Fig. 7 shows another illustrative embodiment of this invention in which the cover 1 is similarly hinged to the chest back or adjacent back extensions 2. The wing sections in this instance however merely comprise the upper side section 28 and framed or connected wing shelf 30 formed with similar retainer devices including the retainer hook 17. When this wing section is swung outward in the position indicated at the left of Fig. 7 it is supported by the heavy brass or other hinge 9 and by the retainer devices which, though not so strong or reliable a construction as shown in Fig. 2, yet has some advantages since the wing section is lighter and does not have any portion sliding over the table or sideboard on which the chest is supported. In this construction the chest front is formed of two sections and the upper front section 31 is hinged at 32 to the lower section so that it can be swung down as indicated in Fig. 7 to expose the wing shelves and the lower articles 14 when the wing sections are swung out so as to render visible this lower part 35 of the chest. In this construction it is desirable to have interlocking grooved portions 29, 33 formed on the front ends of the upper side sections and on the ends of the upper front section so that when these wing sections are swung inward into closed position and the upper front section 31 is swung upward these grooved portions securely interlock and prevent the wing sections swinging or moving outward until the upper front section is again swung down into the position illustrated in Fig. 7.

This invention has been described in con-

nection with a number of illustrative embodiments, forms, proportions, arrangements, parts, devices and materials, methods of manufacture and use, to the details of which disclosure the invention is not of course to be limited since what is claimed as new and what is desired to be secured by Letters Patent is set forth in the appended claims.

10 1. A display case, comprising a bottom and connected back and lower side sections, a chest cover hinged thereto and formed with cover supports to accommodate silverware articles, and a pair of laterally swinging wing sections hinged to said chest and each comprising an upper side section and a wing shelf and a supporting front section forming part of the chest front when the wing section is swung into closed position 15 and cooperating retainer devices on said wing shelf and the lower side section of the chest, a removable tray in the lower part of said chest below said wing shelves and comprising a slotted spacing block to support 20 articles.

2. A display case, comprising a bottom and connected back and lower side sections, a chest cover hinged thereto, and a pair of laterally swinging wing sections hinged to said chest and each comprising an upper side section and a wing shelf, a removable tray in the lower part of said chest below said wing shelves and comprising a slotted spacing block to support articles.

3. A display case comprising a wooden bottom and connected back and lower side sections, a chest cover hinged thereto and formed with cover supports to accommodate silverware articles, and a pair of disengageably hinged laterally swinging wing sections having supports for silverware articles, the lower part of said chest below said wing shelves comprising a spacing block having supporting slots to accommodate articles.

4. A display case comprising a wooden bottom and connected back and lower side sections, a chest cover hinged thereto, and a pair of hinged laterally swinging wing sections having supports for silverware articles.

5. The lower part of said chest below said wing shelves comprising a spacing block having supporting slots to accommodate articles.

5. A display chest comprising a bottom and connected back and lower side sections, a chest cover hinged thereto to accommodate articles, and a pair of connected laterally swinging wing sections each comprising an upper side section, a wing shelf for articles and a supporting front section forming part of the chest front when the wing section is swung into closed position, and a tray for articles in the lower part of said chest below said wing shelves.

6. A display chest comprising a chest body

and a pair of laterally swinging wing sections hinged to said chest body and each comprising an upper side section, a wing shelf and a supporting front section supporting the wing section in swung out positions and forming part of the chest front when the wing section is swung into closed position and cooperating aligning members on said supporting front section and the chest.

7. A display chest comprising a chest body and a laterally swinging wing section disengageably hinged to said chest body and comprising an upper side section, a wing shelf and a supporting front section forming part of the chest front when the wing section is swung into closed position, and cooperating retainer devices on said wing shelf and the adjacent lower side section of the chest and cooperating aligning members on said supporting front section and the chest.

8. A display chest comprising a chest body and a laterally swinging wing section hinged to said chest body and comprising an upper side section and a wing shelf and cooperating retainer devices on said wing shelf and the adjacent lower side section of the chest.

9. A display chest comprising a chest body and a pair of laterally swinging wing sections disengageably hinged to said chest body and each comprising an upper side section, a wing shelf and a supporting front section forming part of the chest front when the wing section is swung into closed position, cooperating interlocking retainer devices on said wing shelf and the adjacent lower side section of the chest to limit the outward and upward movement of the wing section.

10. A display chest comprising a chest body and a pair of laterally swinging wing sections hinged to said chest body and each comprising an upper side section and a wing shelf, cooperating interlocking retainer devices on said wing shelf and the adjacent lower side section of the chest to limit the outward and upward movement of the wing section.

11. A display chest comprising a chest body and a pair of laterally swinging wing sections hinged to said chest body and each comprising an upper side section and a wing shelf, cooperating interlocking retainer devices including a dovetail circular groove on the lower side of said wing shelf to limit the outward and upward movement of the wing section.

12. A display device comprising a spacing block having supporting slots, lined with velvet and cooperating supporting blocks covered with velvet and fitting tightly within said slots to be disengageably retained in vertically adjusted position therein and thereby adjust the capacity of each slot.

13. A display device comprising a spacing block having supporting slots, and co-operating supporting blocks covered with fabric and fitting tightly within said slots 5 to be disengageably retained in vertically adjusted position therein and thereby adjust the capacity of each slot.

14. A display device comprising a spacing block having supporting slots, and co- 10 operating rectangular sectioned supporting blocks covered with cushioning fabric and fitting tightly within said slots to be dis- engageably retained in vertically adjusted position therein and thereby adjust the 15 capacity of each slot.

15. A display device for silverware etc. comprising a spacing block having supporting slots, and co-operating supporting blocks fitting tightly within said slots to be dis- 20

engageably retained in vertically adjusted 20 position therein and thereby adjust the capacity of each slot.

16. A display chest having a bottom provided with article-retaining means, a hinged top provided with a plurality of article-retaining means on its under side, a pair of laterally movable shelf-carrying wings provided with a plurality of article-retaining means on their upper sides, said wings being connected with the chest between its top 25 and bottom and adapted to fold inwardly toward each other over the article-displaying means in the bottom and each comprising side and front portions of the chest, and means carried by the top for locking 30 said wings in closed position.

JOHN LOLO LEE.
